(57) **CLAIM**

The ornamental design for a cushion for respiratory mask, as shown and described.

DESCRIPTION

FIG. 1 is a rear perspective view of a cushion for respiratory mask according to a first embodiment of our design; FIG. 2 is a rear view thereof; FIG. 3 is a front view thereof; FIG. 4 is a top view thereof; FIG. 5 is a bottom view thereof; FIG. 6 is a right side view thereof with the left side view being a mirror image; FIG. 7 is a rear perspective view of a cushion for respiratory mask according to a second embodiment of our design; FIG. 8 is a rear view thereof; FIG. 9 is a front view thereof; FIG. 10 is a top view thereof; FIG. 11 is a bottom view thereof; and, FIG. 12 is a right side view thereof with the left side view being a mirror image.

The use of stippling and shading is provided to show contrast in materials and/or to differentiate between different areas of the design. The claimed design is not limited to the illustrative use of stippling and/or shading.

1 Claim, 4 Drawing Sheets
